UNITED STATES PATENT OFFICE.

JAMES E. MORTON, OF SOUTH NORWALK, CONNECTICUT, ASSIGNOR TO
LUTHER M. WRIGHT, OF SAME PLACE.

DEVICE FOR CLEANSING HATTERS' KETTLES.

SPECIFICATION forming part of Letters Patent No. 617,296, dated January 3, 1899.

Application filed December 28, 1897. Serial No. 663,854. (No model.)

To all whom it may concern:

Be it known that I, JAMES E. MORTON, a citizen of the United States, and a resident of South Norwalk, county of Fairfield, and State of Connecticut, have invented a new and useful Improvement in Devices for Cleansing Hatters' Kettles, of which the following is a specification.

My invention relates to improvements in hat-sizing machines; and it consists in improvements in a device for removing the long hairs and particles of fur which collect in the water.

The drawings show my device in the form in which I now prefer to make it; but it will be understood that I do not confine my invention to the exact form shown, as various modifications may be made without departing from the spirit and scope of my invention.

A hat-former or bat is during the fulling operation frequently dipped in hot water contained in a tank, which is commonly called the "hatter's kettle." During this dipping operation hairs or particles of fur become detached from the bat and remain suspended in the fluid. These hairs or particles of fur if not removed from the kettle attach themselves to the same or other bats subsequently dipped, after these bats have been to a greater or less extent filled, and form what have been termed "dags" in the bat, deteriorating the finish and appearance of the finished article. It has always, as far as I know, been the practice to purify the water in the kettle from time to time by removing these detached hairs and particles of fur. To accomplish this result, it has been the practice time out of mind to pass a strainer of some sort through the water repeatedly by hand. More recently the result has been attained by continuously pumping the water from the kettle and allowing it to return through a screen in which the fibers are caught. Such an apparatus is described in Letters Patent No. 527,187 granted to W. J. Wiley, October 9, 1894. I have discovered that the water within a hatter's kettle is caused to constantly circulate therein with more or less uniformity, due to the application thereto of heat, externally or internally applied, to keep the water at the desired temperature, and that the fibers carried by the current will attach themselves

to any suitable screen made stationary within the path of said current. In other words, I have discovered that all the labor which has been expended in hatter's establishments in removing the fibers by hand has been wasted and that the same and even a superior result will be obtained by allowing the strainer to remain stationary wholly or partially immersed in the water from which the fibers are to be removed, the essential requisite being that the screen shall be placed in the path of a current established by the application to the kettle of heat, whereby the water flows through the screen and the fibers to be removed are arrested by and may be removed with it. This is the gist of my invention.

The apparatus which I now prefer to employ in carrying the invention into effect, as illustrated in the accompanying drawings, may be thus described.

Referring now to the drawings, Figure 1 shows a hatter's kettle with the screen in place. Fig. 2 shows a top view of the screen. Fig. 3 shows a side view of the screen. Fig. 4 shows an end view of the screen.

a is the kettle, made of wood in the usual form.

b is a steam-pipe leading downward and opening into a funnel-shaped piece *c*, which has a series of holes *d* in its sides. The steam issues from these holes and is condensed by the water and the heated water is caused to rise and a current is produced in the kettle in the direction shown by the arrows. The screen *e* is secured to a frame *f*, which has extended ends *f'*, which are provided with notches *g*, which serve to support it on a clamp *h*.

i is a handle for taking the screen off to clean it.

k is a collar secured to the steam-pipe *b* by a set-screw. The clamp *h* is preferably loosely fitted over the steam-pipe and is supported by the collar *k*, so that it may swivel around into any desired position. The screen is supported in place by hooking it onto the clamp *h* by the notches *g*.

In operation I prefer to place the screen just below the surface of the water, as shown by the arrows in Fig. 1, and in the central portion of the kettle; but it will be understood that I may place the screen anywhere

in the path of the flowing water. I may also make the screen of any desired shape and support it from any portion of the kettle, and I do not confine my invention to any particular form of screen nor to any particular place in the kettle.

I will now point out in the claims the particular features of novelty that I claim as my invention, it being understood that the omission of an element from one of the claims is a notice to the trade that the said element is not essential to the combination of said claim.

I claim—

1. In a hatter's kettle, the fluid contained therein combined with means for heating said fluid so arranged as to cause a substantially uniform circulation thereof, fibers contained in said fluid, the specific gravity of which fibers is such that they remain suspended in said fluid and are conveyed about the kettle

by said current and a stationary screen located in the path of the current and fibers by which the latter are arrested and the former purified.

2. A cleansing device for a hatter's kettle, 25 consisting of a screen *e* the frame *ff'*, having the notches *g g*, substantially as described.

3. A supporting device for a screen in a hatter's kettle, the combination of the collar *k*, the swivel-clamp *h* with the screen *e* supported on said clamp, for the purpose specified.

In testimony that I claim the foregoing as my invention I have signed my name, in presence of two witnesses, this 22d day of December, 1897.

JAMES E. MORTON.
